FLASHLIGHT STRUCTURE

George Bailhe, Brooklyn, N. Y., assignor to Fred-craft Corporation, New York, N. Y., a corpora-tion of New York

Application August 27, 1942, Serial No. 456,309

2 Claims. (Cl. 240—10.68)

This invention relates to flashlight structures and more particularly to pocket flashlights or lamp devices of this character.

It is an object of the present invention to provide a flashlight which is inexpensive to manufacture, very efficient during use and operation, and which due to its simplified construction necessitates but a few metallic parts.

It is another object of the present invention to provide a flashlight structure equipped with a reflector which includes luminous means adapted to unobstructedly emanate light rays before, during, or after operation of the flashlight.

A further object of the present invention is to provide a lamp structure including a bulb, reflector means, and luminous means connected with said reflector means, whereby said bulb may unobstructedly project light rays from said lamp structure during operation of said bulb, whereas said luminous means, during inoperative period of said bulb, may also unobstructedly send out light rays and from a continuous surface area on which said luminous means extend.

Still another object of the present invention is to provide means for securing the bulb of the flashlight and simultaneously employing such means as the support for said luminous means.

Yet, a further object of the present invention is to provide luminous means which during the operative period of the flashlight serves as a reflector and during the inoperative period of the flashlight radiates a dim light or emanates relatively weak light rays.

A further important feature of the invention is to provide a flashlight particularly adapted for ordinary use but also in darkened areas, during blackouts, etc.

Still a further object of the present invention resides in the provision of a flashlight which provides not only the usual flashlight service, but also provides an auxiliary or secondary light, such as a continuous glow light resulting primarily from the flashlight's own light source, which activates the aforesaid luminous means automatically even in darkened areas at any time the flashlight is in use or operation, thus making this auxiliary light independent of any outside light source, such as sun rays or the like, but being activatable by them at all times.

These and other new and useful objects may be attained as will appear from the following disclosure of the invention, which consists in the features of novelty in construction, combination and arrangement of the several parts, hereinafter more fully described and shown in the

accompanying drawing illustrating this invention.

In the drawing:

Fig. 1 is a longitudinal sectional view of the flashlight made in accordance with the invention, the flashlight being shown in its assembled and inoperative position.

Fig. 2 is a top plan view of the flashlight of Fig. 1, a part of the flashlight being broken away.

Fig. 3 is a partial sectional view of the housing of the flashlight seen in Fig. 1, but turned 180° from that illustrated in Fig. 1.

Fig. 4 is a longitudinal sectional view of the cap or cover of the flashlight, turned 90° from that shown in Fig. 1, and in a somewhat modified form.

Fig. 5 is a cross-sectional view of a contact member employed in the switch arrangement of the flashlight.

Referring now particularly to the drawing, there is shown in Fig. 1 a flashlight, generally designated by numeral 10 comprising a lower shell or base housing 11 and a cap or cover 12. Housing 11 has the outer wall 13 and the inner wall 14 made of cardboard and pasted together in any suitable manner. Housing 11 may also be made of an ordinary tube of cardboard or the like to which a bottom is attached in form of an end wall. Walls 13 and 14 may have at their upper end a shoulder or neck 15 of reduced diameter to permit slidable frictional engagement with the inner wall of cover 12 at 16 (Fig. 4). The diameter of lower housing 11, when made from ordinary tube material may be the same throughout its length, cover 12 thus slidably engaging the outer wall of the open end of housing 11, which said cover 12 thus embraces and closes. Housing 11 may be adapted to hold two batteries B superpositioned upon each other in a conventional manner. Cover 12 is composed of the outer wall 17 and the inner wall 18, the latter forming a shoulder 19 for glass or similar transparent plate 20 held in position between it and ridge or flange 21 provided at the end of outer wall 17. Within cover 12 there is provided a partition 22 connected to and forming an end wall of inner cover wall 18 and simultaneously a base or seat for a lamp or bulb 23. End wall or partition 22 and wall 18 form the light projecting end of said flashlight. The surface 24 of partition 22, in this example, is substantially flat and provided with a reflector layer, such as luminous coating 24, which may forwardly extend from said partition along the inner wall 18 at 24a to permit unobstructed pro-

jection of the light rays through lens or glass

plate 20. Partition 22 has a central opening for receiving therein bulb 23 which is freely exposed in said projecting end of cover or cap 12, said luminous coating 24 extending substantially rearwardly of said bulb.

Housing 11 has an end wall or a double bottom 25, 26, which forms part of the walls 14, 13, respectively, but may be separately attached to the tubular housing 11, as hereinabove indicated.

As shown in Figs. 1 and 3, on bottom 25 of housing 11, there rests a wire coil 27 supporting battery B, wire coil 27 being part of conductor member 28 which extends between the inner wall 14 and batteries B and terminates at reduced neck portion 15, as at 29. Conductor member 28 passes from inside through shoulder or neck 15 to the outer surface of shoulder 15, as clearly seen in Fig. 3, and may be anchored thereon in any convenient manner.

On the surface of partition 22 and below luminous layer 24 there is fixed a conductor member 30 (Fig. 1) contacting socket of bulb 23 and having an opening through which said bulb socket may protrude. Extension 31 of conductor member 30 is bent inwardly and downwardly to extend along the inner face of outer wall 17 and may be preferably accommodated in a recess or on the face of said wall 17.

It will be evident from the foregoing that upon frictional engagement of inner wall 16 of cap 12 with shoulder 15 of housing 11, cap 12 may be turned so as to bring about increased frictional engagement upon contact between member 31 and member 29. Member 29 bears against the outer surface of shoulder 15. Bulb 23 may be screwed home so that its pole 33 always abuts against battery pole 34, whereas upon rotational movement of contact member 31 (shown in section in Fig. 5) relatively to conductor member 28, the bulb 23 may be switched on and off at will.

It can be realized from the above explanations that the electrical circuit will always be established through contact between bulb pole 33 and battery pole 34 and that interruption of the circuit may be brought about due to rotation of cover or cap 12 (with contact member 31) relatively to housing 11 (with contact member 29), in the direction of arrow A.

It will be apparent that the rays of bulb 23 will be reflected by the luminous layer 24, which upon switching off of light bulb 23 is enabled to emanate from its entire continuous layer surface light rays in darkened areas or during blackouts, so that the flashlight will be very useful for air raid wardens, etc. In Fig. 2 there is shown a mark or arrow 32 which is preferably provided on the luminous reflector means 24, arrow 32 pointing to conductor member 31, so as to enable the operator during blackouts or in darkened areas to easily manipulate cap 12 for bringing contact members 31 and 29 into operative positions.

It is well understood that the housing 11 and cover or cap 12 made of cardboard or similar electrically non-conductive material may be made waterproof or impregnated with any suitable quality improving agent.

Thus, the flashlight made in accordance with this invention is not only useful for the ordinary flashlight service, but also permits a secondary or glow light caused by and resulting from the operation of the electric bulb of the flashlight (own light source).

The luminous glow ordinarily depends on either 75

sunlight or other outside light source for activating the luminous means. In the present case, the flashlight may even solely be used during blackouts or in darkened areas, its own light source being then capable of activating the luminous means, which is effectuated automatically at any time the flashlight will be in operation.

It is, of course, understood that the reflector shown may assume any other desired shape and may be entirely or partly covered by luminous means or layer to bring about the aforesaid effect.

While there have been shown and described and pointed out the fundamental novel features of the invention as applied to the above embodiment, it will be understood that various omissions and substitutions and changes in the form and details of the means illustrated and its operation may be made by those skilled in the art without departing from the spirit of the invention.

Having thus described the invention, what is claimed as new and desired to be secured by Letters Patent is:

1. A flashlight comprising a housing of electrically non-conductive material for containing an electric battery therein, said housing having an open end and being provided with an outer wall, a closure cap made of electrically non-conductive material removably placed over said open end and having an inner wall frictionally engaging with the outer wall of said housing and for sliding movement thereon, electric contact means anchored on the outer surface of said housing wall adjacent said open end and on the inner surface of said cap, respectively, said contact means being adapted to increase the frictional engagement of said cap with said housing when said contact means are in superposition upon movement of said cap on said housing, said cap forming a light projecting end including a partition, a bulb fixed on said partition and freely exposed in said cap, a circuit including said contact means for operating said circuit and connected with said battery and said bulb, and luminous means positioned on said partition substantially rearwardly of said bulb and forming the surface of a reflector, whereby upon relative movement of said cap to said housing make and break of contact between said contact means will be had, so that light rays either from said bulb or from said reflector surface and luminous means pass unobstructedly through said light projecting end.

2. In a flashlight structure having a flashlight body of electrically non-conductive material; a cover of electrically non-conductive material removably mounted on said flashlight body, a partition within said cover forming a seat for the bulb of the flashlight, an extension arranged rearwardly of said partition for removably and slidably mounting said cover on the flashlight body, a wall within said cover forwardly extending from said partition, said wall together with said partition forming the light projecting end of said flashlight, and a luminous coating disposed on said partition and on said wall, whereby light rays from the bulb may be unobstructedly projected through said light projecting end, said luminous coating being adapted to unobstructedly emanate light rays from said light projecting end when the bulb of said flashlight is not in use.

GEORGE BAILHE.
